G. W. FLYNN

SELECTIVE SIGNALING SYSTEM

Filed March 2, 1921

21

Fio. 1

UNITED STATES PATENT OFFICE.

GEORGE WILLIAM FLYNN, OF BLUNDELLSANDS, NEAR LIVERPOOL, ENGLAND.

SELECTIVE SIGNALING SYSTEM.

Application filed March 2, 1921, Serial No. 449,103, and in Great Britain July 4, 1919.

(GRANTED UNDER THE PROVISIONS OF THE ACT OF MARCH 3, 1921, 41 STAT. L. 1313.)

The present invention relates to electric signaling systems such as are used for selectively signaling one or more stations connected to a common line or so called "omni-bus" circuit.

A considerable difficulty has been experienced hitherto in selecting stations where the number of these connected to one line is large, say in the neighborhood of 100, and consequently the equipment installed, has been proved to be either unduly expensive on account of the intricate nature of the apparatus or has failed to give satisfactory and reliable results under the exceptionally adverse conditions of working to which such systems are subjected.

The object of the present invention is to provide simplified apparatus at each out-station and at the control station which will be reliable and satisfactory and at the same time will enable the number of stations to be increased up to say, a hundred, without any additional features in the substation apparatus.

According to the invention, the out-stations are selected by means of a number of independent series of impulses which may be produced by the agency of a dial-switch of identical construction with those used in automatic telephone systems, operated at the signaling or control station. The out-stations are provided with a selective device such as a rotary or like switch in which a driving magnet causes a wiper to successively pass over and make contact with a series or bank of contacts. Each out-station is identical except for simple connections to certain contacts which connections are peculiar to the station, and also other similar connections peculiar to either a group or to the whole of the stations if it is desired to ring up either a particular group or the whole of the stations at once.

Each station will be numbered, usually in the decimal notation, to correspond to the ten impulses sent by the well known dial switch. Then, if there are not more than a hundred stations which will usually be the case, only two digits would be dialled. The dialling of the tens digit would cause the switches at every station to operate, but in

only ten cases would the wiper rest on a contact which was connected up so as to prepare a circuit in order that the bell to be selected may be rung on the dialling of the units digit. This next dialling then effects a second operation at each of these ten stations and preferably the further operation of the switches already operated. This next dialling moves the wiper to another contact which only in the case of the station required, will be connected up to complete the operation and effect the ringing of the bell.

Arrangements are provided for enabling the out-station to ring up the control station, also a means is incorporated of letting the control station know when the bell at the out-station selected is ringing in response to the operation of dialling.

Further details of the invention will be better understood by referring to the accompanying drawings which illustrate one method of carrying out the invention by way of example. Fig. 1 shows diagrammatically the connections of the apparatus at the control station and the out stations, Fig. 2 shows diagrammatically one form of dial switch employed.

The apparatus at station C which is the calling or control station, is provided with a speaking or ringing key 1, through which the operator's instruments are connected to the line A B. An impulse relay 5 is adapted to be connected through the springs 6 and 7 of key 1 with the circuit battery 150, a dial switch or calling device 3 of the type usually used on automatic telephones being connected with its contact springs 3' and 3" in series with the relay 5 and battery 150. The construction of the dial switch 3 is more particularly shown in Fig. 2. The relay 5 functions to reverse the polarity of the battery 4 on each interruption of the current passing through the relay 5 by the dial switch 3. To prevent the outgoing impulses being overheard by the operator the dial switch 3 is provided with an auxiliary pair of springs 59 arranged to short circuit the winding 57 of induction coil 58 when the dial is off normal due to the sending of the impulses.

The speaking side of the key 1 is connected to the line A B through spring 8, wire 71, spring 72 and also through spring 19, spring 79, wire 79^a and spring 78. The speaking set comprises receiver 76, induction coil 58 having windings 57, 74, 75 and 84, transmitter 85, cut out switch 83, and inductive resistance 86.

A bell 97 and line lamp 95 are connected 16 also to the line A B when the springs of the speaking side are in normal position, by the following arrangement. Springs 89, 91 of key 1, sensitive line relay 90, which latter operates to complete the circuit of relay 92 15 through earth, battery, springs 81 and 94 of key 1, contact 93, lamp 95, relay 96 to earth and also associated circuit of bell 97.

At each out station D, E, F, a polarized relay 20 is connected across the line A B 20 through normally closed springs 21, 22 of key 20^a, noninductive resistance 23, winding 24 of relay 20, springs 25, 26 of key 20^a to line B. The relay 20 operates to close one of two circuits through contacts 28, 29 25 or 28, 32. The former closes the circuit of a slow acting relay 27 and the contacts 28, 32, when this latter circuit is closed close the circuit of a rotary selective switch 38 through a stepping magnet 36 and holding relay 35 in parallel.

The rotary switch 38 comprises a number of contacts in this case twenty-one in number, such as 37 forming the arc of a circle, a contact arc 40, wiper 39 adapted to contact 25 with the individual contacts of the arc 40. The wiper 39 is stepped around by the impulses passing through the electro-magnet 36 which operates suitable stepping mechanism such as a pivoted pawl engaging with 40 teeth mounted on a circular plate connected with the wiper 39. Mounted on the said plate is a projection 110 adapted to separate a pair of contact springs 48 when the wiper is at zero position. A release magnet 69 45 operating detent 70 holding the toothed plate of the wiper arm 39 is also provided and operates as hereinafter described. Associated with the rotary switch 38 is a bus bar device 111 comprising a similar number of 50 terminals such as 42, 52, 101, as are provided on the switch 38, a tens bar 44 and units bar 53. Each of the contacts of the rotary switch 38 is connected to the corresponding terminal of the device 111, or at least some 55 connections are made, as will be later described. According to the number of the outstation the tens bar 44 is connected to that terminal of the device 111 corresponding to the tens digit and the tens bar 44 60 therefore lies adjacent the first ten terminals only. The units bar 53 is connected to that terminal of the device 111 which corresponds to the sum of the tens and units digits of the outstation. For example if the number of 65 the station is 53 the tens bar 44 is connected

to the 5th terminal and the units bar to the 8th terminal as shown in the figure. All stations have terminals 98 and 99 connected by a link, if desired as also terminal 100 and 70 102. Associated with the tens bar 44 is a 75 circuit including contact 45 of holding relay 35, relay 47 and earth. Connected with the units bar 53 is a circuit comprising contact 54 of relay 47, contact 46 of relay 35, bell 55, winding 56 of relay 20 and earth.

A speaking set including receiver 60 and transmitter 65 is connected across the line A B through a switch having a plurality of springs 63, 64, 66, 67, 68 the function of which will be hereinafter described. A condenser 61 and induction coil 62 are inserted in the circuit as shown.

If it is desired to call up the operator at station C from the outstations D, E, F, etc., the operation of the calling key 20^a connects 85 a ringing battery from earth through springs 88, 21 to line A, through operation indicating devices, line B, springs 26, and 87 of key 20^a to the earth.

Fig. 2 shows a suitable form of dial 90 switch or calling device. This comprises a finger plate 115 having perforations 116 and 95 rotatably mounted on a central spindle 119. Below the plate 115 is a further fixed number plate having numbers 118 thereon from 1-9 and 0. Pivottally mounted on the plate 115 is a pawl 121 adapted to engage the teeth of a ratchet wheel 120 capable of rotational movement about the spindle 119. Rigidly secured to the ratchet 120 is a cam wheel 122 provided with a plurality of teeth or projections corresponding to the numbers mounted on the number plate.

The dial switch is provided with a pair of interrupter contact springs 3' and 3'' and 105 also a pair of off normal contact springs 59 the longer one of which engages with an insulated pin 123 adapted to hold the springs out of contact in the normal position. A finger stop 124 is rigidly secured to the back 110 plate 117.

To dial a number or digit the finger is inserted in the opening 116 of the finger plate 115 through which the required number on the number plate 117 can be seen and the plate 115 is rotated in a clockwise direction until the finger abuts against the stop 124. By this action the pawl 121 is carried over a number of teeth of the ratchet wheel 120 corresponding to the number selected and tensions, spiral or the like springs (not shown) usually assembled about the spindle 119. On the releasing of the finger plate 115 the spring returns the plate to its normal position and in consequence, the movement of the pawl 121 rotates the ratchet wheel 120 and therewith the cam wheel 122 in anti-clockwise direction thus causing the projections on the cam 122 to ride over the spring 3'' and to cause the same to break 125 130

contact with the spring 3' according to the number dialed.

When the plate 115 is moved from its normal position the pin 123 being removed from the longer of the off normal contact springs 59 allows contact to be made between the two which remain in contact all the time the plate 115 is away from its normal position.

To ensure uniformity in the interruptions 10 of contact springs 3' and 3'' a suitable governing device may be incorporated in the mechanism of the switch thereby controlling the return movement of the plate 115.

Referring to Figure 1 the operator's set 15 includes a speaking and dialling key 1, a speaking set 2, a dial switch 3 which may be of the well known type as used in automatic telephony, and line battery 4.

When the operator wishes to call a party 20 on the line he presses the key 1 to the right. The effect of this is to operate the impulse relay 5 through the circuit battery 150, key springs 6 and 7, dial springs 3', relay 5 to earth. This relay reverses the polarity of 25 battery 4 which as an additional effect of operating key 1, is connected to line through the following circuit, from A line through contacts 8 and 9 of key 1, through resistance 159, inductances 10 and 11, contacts 12 and 30 13 of relay 5 to positive pole of battery and thence from negative pole of battery through contacts 14 and 15 of relay 5, inductances 16 and 17, contact springs 18 and 19 of key 1 to B line.

At each out-station the effect of connecting battery 4 to line is to operate the polarized relay 20 of that station through the following circuit from positive pole of battery connected to line A through springs 21 and 40 22 of calling key 20^a, through a non-inductive resistance 23, winding 24 of relay 20, through springs 25 and 26 of calling key 20^a to negative pole of battery connected to B line. The polarized relay 20 operates in 45 such a manner as to close the circuit of the slow releasing relay 27 through its contacts 28 and 29. The operator at the control station then works the dial to send impulses to line in accordance with the number of the 50 wanted party. Assume that the party wanted is number 53. He will then dial 5 breaking the circuit of impulse relay 5 times. The impulse relay allows its armatures to fall back and reverse the polarity of battery 55 connected to line as will be seen from tracing the circuits, line A instead of being connected to positive pole of battery 4 through springs 12 and 13 will be connected to negative pole of battery through springs 12 and 30 and line B will similarly be connected to positive pole of battery through springs 15 and 31.

The effect of these momentary reversals of current is to cause all the polarized relays 60 20 connected across the line to operate so

that the contact member 28 momentarily makes contact with contact 32. The first impulse closes a circuit as follows: earth, contact 28 and 32 of relay 20, contacts 33 and 34 of relay 27, which being slow acting will not fall back for momentary breaks in its circuit, slow acting holding relay 35 and driving magnet 36 in parallel, to normal contact 37 of rotary switch 38, wiper 39, arc 40 to earthed battery 140. The driving magnet operates to step the wiper 39 one step, which breaks the battery connection through contact 37, a further connection to battery 141 being made by means of the contact springs 41 of relay 35 which being of the slow release type remains operated during the subsequent impulses of the same series. The remaining four impulses therefore due to the contacts 28 and 32 making and breaking so many times cause the driving magnet to step the wiper 39 to the fifth contact 42^a from normal. The effect of this is to connect positive pole of battery 140 to the fifth terminal 42 in the row of 21 terminals shown at the lower right hand corner of the figure. The 20 contacts of the rotary switch are connected to these 21 terminals by conductors as shown diagrammatically in the drawings, the twenty-first terminal and tenth terminal being connected together for reasons to be explained later.

At all stations whose numbers have 5 for the first digit a wire link is provided connecting the fifth terminal to a bus bar 44 termed a "tens bar" which is placed adjacent to the first ten terminals as shown.

Now after the first five impulses have been sent there is a slight interval which permits the relay 35 to de-energize, allowing the contacts 45 and 46 to close and contact 41 to open.

The result of this is that the following circuit is closed in the ten stations whose first digit commences with 5, but not in any of the other stations: battery 140, arc 40, fifth contact 42^a, fifth terminal 42, tens bar 44, contacts 45 of relay 35, relay 47 to earth. A circuit had previously been closed through relay 47 from battery 148, off normal springs 48 (now closed) of rotary switch resistance 49, relay 47 to earth, but the current through this circuit while sufficient to maintain the relay 47 operated is insufficient to operate it by itself due to the resistance 49; consequently the relay 47 is operated through the first mentioned circuit and is subsequently maintained operated through the second circuit.

The operator then proceeds to dial the units digit 3, the effect of the first impulse is to send an impulse of current through the following circuit: earth, contacts 28 and 32 of polarized relay 20, contacts 33 and 34 of relay 27, relay 35 and driving magnet 36 in parallel, connection point 142, contact 50 and

51 of relay 47, tens bar 44, cross connecting link to terminal 42, thence to its corresponding contact 42^a on rotary switch through wiper 39, arc 40 to battery 140.

5 It will be noted that the impulse will be without effect at all other stations than those whose first digit is five due to the starting impulse having to pass through a wire link on the fifth terminal which is only 10 present in such stations.

The holding relay 35 operates as before connecting battery 141 through contact 41 for the subsequent operation of the driving magnet in lieu of that supplied through the 15 fifth contact and wire link which is removed on the advance of the wiper 39. The driving magnet operates to step the wiper to the sixth contact and with the two subsequent 20 impulses steps it to the eighth contact 52^a when the dialling being completed the holding relay 35 is deenergized. At station numbered 53 there will be a second connecting link joining the eighth terminal 52 to a second bus bar 53 placed adjacent the 25 second to nineteenth terminals and termed the units bar.

Consequently when the wiper rests on the eighth contact sufficiently long for the relay 35 to be de-energized a circuit will be closed 30 as follows: battery 140, arc 40, wiper 39, eighth contact 52^a, eighth terminal 52, wire link to units bar 53, thence through contact 54 of relay 47, contact 46 of relay 35, bell 55 through a few turns 56 on polarized relay 20 to earth. The bell rings and at the 35 same time by means of the winding 56 on polarized relay 20, a current is induced on the line which can be heard by the control station operator due to the provision of a winding 57 on the induction coil 58 of his speaking set 2 which is tapped off the inductance 10 in series with the impulse circuit.

In order to avoid the outgoing impulses 40 being overheard by the operator the dial switch 3 is provided with an auxiliary pair of springs 59 arranged to short circuit the winding 57 of induction coil 58 when the dial is off normal due to impulses being sent.

The called party at station No. 53 hearing 45 his bell ring, lifts his receiver 60 to connect his speaking set in circuit, the receiver 60, being connected across the line in series with the condenser 61 and secondary winding of induction coil 62 by means of the switch hook springs 63 and 64 while the transmitter 65 is connected to battery 165 through the primary of induction coil 62 and switch springs 66 and 67. A circuit is 50 momentarily closed on lifting the receiver, from battery 165, switch springs 67 66 and 68 and release magnet 69 to earth. The release magnet operates to remove detent 70 from ratchet wheel of rotary switch which

immediately restores to normal; the off normal springs 48 then break contact and relay 47 de-energizes. At the same time the bell circuit is broken.

The operator then noticing the cessation 70 of the ringing tone places his key 1 to the speaking position (i. e. to the left) connecting speaking set across the line over the following circuit: line A, springs 8 and 71, 72 and 73 of key 1, winding 74 of induction coil 58, winding 75 and receiver 76 in parallel springs 77, 78, 79 and 19 of key 1 to line B. The transmitter receives current 75 through the circuit, battery, springs 81 and 82 of key 1, transmitter cut out springs 83, winding 84 of induction coil 58, transmitter 85, inductive resistance 86 to earth. Conversation can then be carried on. The operator in moving his key to the speaking position breaks the connection of battery 4 to line at springs 8 and 9 and at springs 18 and 19 while at springs 6 and 7 the circuit of relay 5 is permanently broken, this relay therefore de-energizes.

The removal of current from the line causes the polarized relays 20 at every station on the line to restore to their normal position with the contact 28 midway between contacts 29 and 32 and making contact with neither. The result is that the 80 relay 27 de-energizes. Consequently the following circuit is closed at contact 80, battery 148, off normal springs 48, contact 80, release magnet 69 to earth. It will be understood that this occurs at every station 85 on the line, except the selected station, as every rotary switch has moved either to the fifth or the eighth contact and therefore the off normal springs 48 are closed.

Upon the rotary switches 38 returning to 90 normal, the off normal springs 48 break contact, breaking the circuit of the release magnet and also the circuit of the relay 47, so that every station is restored to normal.

When the conversation is finished the 95 called party restores his receiver to the switch hook and the operator places his key in the normal position. It will be appreciated that in order to ring any out-station bell it is necessary to operate the relay 47 which depends upon the tens digit and subsequently to operate the bell which depends upon the units digit, and upon the operation of relay 47. For instance, in the case of station 62, his rotary switch will remain on the 100 fifth contact, and will not be further operated, so that although the same total number of digits are dialled, (as in the typical example 53) an entirely different result ensues. Similarly it will be appreciated that only one of a hundred stations will be rung up if the cross-connecting links at each station are arranged correctly, for instance number 11 will be connected with 1st terminal connected to tens bar and 2nd termin- 105

nal to units bar, number 16 with 1st terminal to tens bar and 7th terminal to units bar, number 43 with 4th terminal to tens bar and 7th (4+3) terminal to units or generally number "ab" with a^{th} terminal to tens bar and $a+b^{\text{th}}$ terminal to units bar.

It should be mentioned that the invention is not strictly limited to two digits although it is believed in practice that the difficulties on most lines of having more than a hundred parties on the line will be too great, except in very exceptional circumstances to render this of much use.

If any of the out-stations desires to attract the attention of the control station operator, this may be done by pressing the calling key 20^a which connects battery across the line through the circuit battery, springs 88 and 21 of calling key 20 to line A, thence to springs 8, 71, 72, 89 of key 1, sensitive line relay 90, springs 91, 78, 79 and 19 of key 1 to line B and thence through springs 26 and 87 of calling key 20^a of calling station to earth.

The line relay is designed to respond to this current, while the polarized relays 20 are preferably arranged as to be incapable of responding. Relay 90 operates and closes the circuit of relay 92 which locks itself over the circuit-earth, relay 92 and its contact 93, springs 94 and 81 of key 1 to battery at the same time the line lamp 95 illuminating in series with the night alarm relay 96 which is adapted to close the circuit of the night bell 97. As soon as the control station operator operates his key to the speaking position the locking circuit of relay 92 is broken and the lamp 95 is extinguished.

In certain cases it is often desirable for the controller to communicate with all the out-stations at once or to communicate with all the stations of a given group and this may readily be effected by the following arrangement.

It will be assumed first of all that the controller desires to communicate with all the stations at once, in order to effect this the twentieth terminal 98 of each station is connected by a cross connecting link to an auxiliary terminal 99 adjacent with the units bar; also the twenty-first terminal 100 is wired to the tenth terminal 101 permanently as shown while a cross connecting link connects it to a second auxiliary terminal 102. In order to call all the stations the controller dials 0 0 (0 signifying ten impulses).

The dialling for the tens digit is similar to that previously described, the rotary switches all being brought with their wipers 39 on the tenth contact from normal. At those stations at which there is a cross connecting link from the tenth terminal to the tens bar the subsequent dialling causes the instruments to operate as previously described with reference to the calling of sta-

tion 53; at the other stations, the relay 47 is not operated and consequently a circuit is closed as follows for the first impulse of the units digit: earth, contact 28 and 32 of relay 20, contact 33 and 34 of relay 27, relay 35 and driving magnet 36 in parallel, contact 50 and 103 of relay 47, terminal 102, cross connecting link to terminal 100, thence to tenth contact of rotary switch, wiper 39, arc 40, to battery. Relay 35 operates and remains operated through the subsequent series of impulses to hold contacts 41 closed so that driving magnet 36 continues to respond to the impulses at every station, consequently on the tenth impulse of the units digit the wiper 39 comes to rest upon the twentieth contact, the following circuit being closed: earth, battery, arc 40, wiper 39, twentieth contact to terminal 98, cross connecting link to terminal 99, contact 46 of relay 35, bell 55, winding 56 of relay 20 to earth. As it is only necessary for the twentieth contact to be reached, the bells at every station will ring.

It will be appreciated that by neglecting to provide cross connecting links between terminals 98 and 99 or 100 and 102 at any stations these stations may be made exceptions to the general rule. Similarly other group calls may be arranged by suitably connecting certain of the group of terminals with the tens and units bars, in addition to the connections appropriate to the individual numbers of the respective instruments, and in this way groups of stations may be rung at a time.

For instance it may be decided that the number 53 instead of being the number of a station is the number of a group call. Then all stations belonging to that group will have connecting links from the fifth terminal to the tens bar and from the eighth terminal to the units bar preferably the members of the group will all have 5 for their first digit, this will avoid unnecessary complications.

It will be appreciated that a very efficient selective signalling system capable of dealing with a large number of stations has been evolved, at the same time it must be understood that the invention is by no means limited to the construction described as several modifications may be made therein without departing from the spirit of the invention.

Among other modifications it will be appreciated that it is by no means essential that the impulses should consist of reversals of current. The reason for employing reversals instead of a direct make and break is to increase the reliability of the system, it being well known that for long lines on which the invention will usually be employed a reversal of current operating a polarized relay is more effective than a simple make or break. Further, the arrange-

ment of inductances 10, 11, 16 and 17 with the condensers 104 and 105 in shunt as shown in the drawings is not essential but is desirable for the efficient transmission of the impulses over a long line.

Also, it must be understood that the arrangement of batteries shown is only conventional and it is by no means essential that there should be an earth connection at either the out station or the controller's station as regards the battery. Further there will usually be only one or at most two batteries at each out-station, one for the transmitter circuit and one for the driving magnet and the operating relays.

I declare that what I claim is:—

1. In a selective signaling system the combination of a central station, a plurality of outlying stations each having a designation number, a common line connecting said stations, means at said central station to transmit over said line a plurality of series of impulses, an indicating device at each of said outlying stations, a rotary selective switch at each of said outlying stations having a single rotary arm and a plurality of contacts, means to drive said arm in response to the first series of impulses received from said central station, an electrical circuit at each outlying station connected to a contact of said rotary switch corresponding to the first digit of said designation number, means controlled by current in said circuit to cause said driving means of said rotary arm to be re-actuated on the transmission of a subsequent series of impulses and a second electrical circuit connecting a contact of each of said rotary switches corresponding to the sum of the digits of said designation number to said indicating device.

2. In a selective signaling system the combination of a central station, a plurality of outlying stations each having a designation number, a common line connecting said stations, means at said central station to transmit over said line a plurality of series of impulses, an indicating device at each of said outlying stations, a rotary selective switch at each of said outlying stations having a single rotary arm and a plurality of contacts, means to drive said arm in response to the first series of impulses received from said central station, an electrical circuit at each outlying station connected to a contact of said rotary switch corresponding to the first digit of said designation number, means controlled by current in said circuit to cause said driving means of said rotary arm to be re-actuated on the transmission of a subsequent series of impulses, a second electrical circuit connecting a contact of each rotary switch corresponding to the sum of the digits of said designation number to said indicating device and means controlled by said first circuit to

establish a current in said second circuit on the completion of transmission of a succeeding series of impulses.

3. In a selective signaling system the combination of a central station, a plurality of outlying stations each having a designation number, a common line connecting said stations, means at said central station to transmit over said line a plurality of series of impulses, an indicating device at each of said outlying stations, a rotary selective switch at each of said outlying stations having a single rotary member and a plurality of contacts, means to rotate said arm in response to the first series of impulses received from said central station, an electrical circuit at each outlying station connected to a contact of said rotary switch corresponding to the first digit of said designation number, a second electrical circuit including a battery and the rotating means for said rotary arm, switch means in said second circuit controlled by current in said first circuit, and a third electric circuit connecting a contact of each of said rotary switches corresponding to the sum of the digits of said designation number to said indicating device.

4. In a selective signaling system the combination of a central station, a plurality of outlying stations each having a designation number, a common line connecting said stations, means at said central station to transmit over said line a plurality of series of impulses, an indicating device at each of said outlying stations, a rotary selective switch at each of said outlying stations having a single rotary arm and a plurality of contacts, means to drive said arm in response to the first series of impulses received from said central station, an electrical circuit at each outlying station connected to a contact of said rotary switch corresponding to the first digit of said designation number, means controlled by current in said circuit to cause said driving means of said rotary arm to be re-actuated on the transmission of a subsequent series of impulses, a second electrical circuit connecting a contact of each of said rotary switches corresponding to the sum of the digits of said designation number to said indicating device, a spring controlled pawl adapted to hold said rotary arm in position after each series of impulses, and an electromagnetic releasing device to withdraw said pawl and to restore said rotary member to normal.

5. In a selective signaling system the combination of a central station, a plurality of outlying stations each having a designation number, a common line connecting said stations, means at said central station to transmit over said line a plurality of series of impulses, an indicating device at each of said outlying stations, a rotary selective switch

at each of said outlying stations having a single rotary arm and a plurality of contacts, means to drive said arm in response to the first series of impulses received from said central station, an electrical circuit at each outlying station connected to a contact of said rotary switch corresponding to the first digit of said designation number, means controlled by current in said circuit to cause said driving means of said rotary arm to be re-actuated on the transmission of a subsequent series of impulses, a second electrical circuit connecting a contact of each of said rotary switches corresponding to the sum of the digits of said designation number to said indicating device, a spring controlled pawl adapted to hold said rotary member in position after the series of impulses and an electromagnetic releasing device to withdraw said pawl on response of the station selected.

6. In a selective signaling system the combination of a central station, a plurality of outlying stations each having a designation number, a common line connecting said stations, means at said central station to transmit over said line a plurality of series of current impulses, an indicating device at each of said outlying stations, a rotary selective switch at each of said outlying stations having a single rotary arm and a plurality of contacts, means including an electromagnet to drive said rotary arm in response to the impulses received from said central station, a source of current, an electrical circuit connecting said electromagnet to said source of current and means to break said circuit automatically upon said rotary arm coming to rest after the transmission of the first of said series of impulses.

7. In a selective signaling system the combination of a central station, a plurality of outlying stations each having a designation number, a common line connecting said stations, means at said central station to transmit over said line a plurality of series of impulses, an indicating device at each of said outlying stations, a rotary selective switch at each of said outlying stations having a single rotary arm and a plurality of contacts, means to drive said arm in response to the first series of impulses received from said central station, an electrical circuit at each outlying station connected to a contact of said rotary switch corresponding to the first digit of said designation number, means controlled by current in said circuit to cause said driving means of said rotary arm to be re-actuated on the transmission of a subsequent series of impulses, a second electrical circuit connecting a contact of each of said rotary switches corresponding to the sum of the digits of said designation number to said indicating device, a spring controlled pawl adapted to hold said rotary arm in position

after each series of impulses, an electromagnetic releasing device to withdraw said pawl and to restore said rotary member to normal, a telephone circuit at said central station, a speaking key at said central station to connect said telephone circuit across said common line and means to operate said electromagnetic releasing device upon the movement of said key into the speaking position.

8. In a selective signaling system the combination of a central station, a plurality of outlying stations each having a designation number, a common line connecting said stations, means at said central station to transmit over said line a plurality of series of impulses, an indicating device at each of said outlying stations, a rotary selective switch at each of said outlying stations having a single rotary arm and a plurality of contacts, means to drive said arm in response to the first series of impulses received from said central station, an electrical circuit at each outlying station connected to a contact of said rotary switch corresponding to the first digit of said designation number, means controlled by current in said circuit to cause said driving means of said rotary arm to be re-actuated on the transmission of a subsequent series of impulses, a second electrical circuit connecting a contact of each of said rotary switches corresponding to the sum of the digits of said designation number to said indicating device, a tens bar included in said first electrical circuit, and a units bar connected in said second electrical circuit, additional pairs of terminals, connecting links between the terminals of each pair, means to connect one terminal of one pair to a predetermined switch contact at each outlying station, means connected to the other terminal of said pair to apply current to said driving means when said rotary arm comes to rest on the predetermined contact of said rotary switch, and connecting means between said other pair of terminals and said indicating device.

9. In a selective signaling system the combination of a central station, a plurality of outlying stations each having a designation number, a common line connecting said stations, means at said central station to transmit over said line a plurality of series of current impulses, an indicating device at each of said outlying stations, a rotary selective switch at each of said outlying stations, having a single rotary arm and a plurality of contacts, an electromagnet to drive said rotary arm in response to the impulses received from said central station, a source of current, an electrical circuit connecting said electromagnet to said source of current, means to break said circuit automatically upon said rotary arm coming to rest after the transmission of the first of said series of impulses, a tens bar, a connecting link be-

tween one of said switch contacts corresponding to the first digit of said designation number and said tens bar, a relay having a coil element and a contact element, a second source of current, a second electrical circuit including said connecting link and the coil element of said relay and means controlled by said relay to apply said second

source to said electromagnet when said rotary arm rests on said contact corresponding to the first digit of said designation number. 10

In witness whereof, I have hereunto signed my name this 7th day of February 1921.

GEORGE WILLIAM FLYNN.
